BEET HARVESTING AND TOPPING MACHINE

Louis A. Geibig, Los Angeles, Calif.

Application December 7, 1935, Serial No. 53,338

16 Claims. (Cl. 55—9)

My invention relates to beet harvesting and topping machines, and the objects of my invention are:

First, to provide a beet harvesting and topping machine with means for removing the beets from the ground as the machine moves forward and with means for removing the beet tops from the beets;

Second, to provide a machine of this class in which the means for removing the beet tops remains stationary until beets are presented to it by the machine;

Third, to provide a machine of this class in which soil carried from the ground with the beets may fall back to the ground at any time before reaching the means for removing the beet tops;

Fourth, to provide a machine of this class in which the means for removing the beets from the ground not only engage and lift but also pull the beets from the ground;

Fifth, to provide a machine of this class in which the means for removing the beets from the ground may be elevated or lowered at any time while the machine is in operation or is standing;

Sixth, to provide a machine of this class which will not operate while it is moving backwardly;

Seventh, to provide a machine of this class in which the motivating force for all its parts is derived from its traction in its forward motion over the surface of the ground; and,

Eighth, to provide a machine of this class which is very simple and economical of construction in proportion to its functions, easy to operate, efficient in its action, and will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a longitudinal vertical sectional view taken centrally through the machine with parts and portions shown in elevation to facilitate the illustration; Fig. 2 is a fragmentary sectional view along the line 2—2 of Fig. 1; Fig. 3 is a fragmentary transverse sectional view taken along line 3—3 of Fig. 1 looking towards the front end of the machine showing parts and portions in elevation and other parts broken away to facilitate the illustration, and showing the mechanism for raising and lowering the digger points with

the digger points in their extreme lower position; Fig. 4 is a fragmentary plan sectional view along the line 4—4 of Fig. 3; Fig. 5 is a fragmentary transverse sectional view taken looking towards the rear end of the machine along line 5—5 of Fig. 1 and with parts and portions shown in elevation to facilitate the illustration and particularly showing the topping mechanism clutch in its engaged relation; Fig. 6 is a fragmentary sectional view of the conveyor sprocket support member on an enlarged scale and with parts and portions shown in elevation; Fig. 7 is a fragmentary sectional plan view taken along 7—7 of Fig. 1 of the rear end of the machine showing the topping mechanism clutch in its disengaged position; Fig. 8 is a sectional view on an enlarged scale, along line 8—8 of Fig. 7, showing the axle in elevation, and showing the topping mechanism clutch disengaged; Fig. 9 is an enlarged fragmentary sectional view along line 9—9 of Fig. 7 of the cam for disengaging the topping mechanism clutch; Fig. 10 is a fragmentary sectional view of the cam taken at a right angle to Fig. 9 and along the line 10—10 of Fig. 9; Fig. 11 is a fragmentary sectional view along line 11—11 of Fig. 1 but showing the elevator topping pan in its extreme upper position; Fig. 12 is a fragmentary sectional view along line 12—12 of Fig. 7 with parts and portions shown in elevation to facilitate the illustration; and Fig. 13 is a fragmentary sectional view on an enlarged scale along the line 13—13 of Fig. 12.

Similar characters of reference refer to similar parts and portions throughout the several views of the drawings.

Frame members 1, rear wheels 2 and 3, rear axle 4, combined clutch jaw and gear 5, clutch jaw 6, clutch collar 7, gear 8, gear 9, gear bracket 10, cam plate 11, link member 12, link member 13, elevator topping pan 14, elevator guides 15 and 16, elevator discharging mechanism 17, discharge mechanism support 18, clutch link member 19, conveyor sprocket supports 20 and 21, transverse member 22, conveyor sprockets 23 and 24, conveyor chain 25, conveyor guides 26, digger points 27, digger elevator 28, front wheels 29, front axle 30, and journals 31 and 32 constitute the principal parts and portions of my beet harvesting and topping machine.

The frame member 1 consists principally of two longitudinal members 1a and 1b held in spaced apart relation at the forward end by transverse member 1d and at the rear end by transverse member 1c, all secured together to form a rigid frame. This frame member 1 is provided with a

transversely disposed rear axle, 4, secured to longitudinal member 1a by journal 32 and to the longitudinal member 1b by journal 31 as shown in Figs. 1, 5, and 12. It will be noted in Fig. 12 that a reduction in axle diameter at 4a and a corresponding reduction in the journals' internal diameters at 32a serves as a collar on the end of the axle, 4, so as to prevent any transverse movement of said axle. Positioned upon axle 4 and centrally spaced between the longitudinal frame members 1a and 1b, as shown in Figures 5 and 7, is the combined clutch jaw and gear 5. Said combined clutch jaw and gear is free to rotate upon the axle 4; but so that it will have no motion along axle 4, member 5 is confined to its central position by means of collars 5a and 5b which are secured to axle 4 by means of set screws 5c and 5d respectively as best shown in Figure 8. The combined clutch jaw and gear member 5 is composed of a spur gear portion 5e which is constantly in mesh with a spur gear 8, and a clutch jaw portion 5f, the lugs, 5g, of which may be engaged by the lugs 6a of the clutch jaw 6. However, clutch jaw member 6, unlike member 5, is not free to rotate upon axle 4, but because of pin 6b extending through the axle 4 and into slots 6c and 6d, as shown in Fig. 8, must rotate with axle 4. It will be noted that the slots 6c and 6d are of sufficient length to permit member 6 to shift along the axle 4 so that the lug 6a can engage the lug 5g of member 5 as shown in Fig. 5 or be disengaged as shown in Figures 7 and 8. It will be noted, as shown in Fig. 8 that clutch jaw 6 has an internal bore 6f of sufficient length and diameter to receive collar 5b when it is in engagement with clutch jaw 5f, and further, that the collar 5b is of sufficiently smaller outside diameter than the diameter of the bore so that there is no contact between members 5b and 6f.

To keep clutch jaw member 6 in its disengaged position a groove 4e around shaft 4 is provided wherein ball member 6g runs as the shaft turns. Backing the ball 6g is a spring 6h all of which is secured within bore 6j by threaded plug 6i. Similarly, to keep clutch jaw 6 in its engaged position, a groove 4f is provided, all as shown best in Fig. 8. Around the end of member 6 opposite to the end having the lugs 6a is a clutch collar 7 seated in groove 6e as shown in Fig. 8. This groove 6e extends completely around the circumference of the clutch jaw member 6, and the portion of the clutch collar riding therein makes a running fit therewith. In conjunction with the clutch collar 7 is a sleeve portion 1a positioned around axle 4 and integrally connected with the clutch collar 7 by member 7b as shown by Figures 5, 7, and 8. This sleeve 1a is of large enough diameter that it can shift along axle 4. The sleeve portion 1a at 7d is pivotally connected with link member 1c, which link member is also pivotally connected to the cross support member 1c of the frame 1 at 7e as shown in Fig. 7. Connected by its end to the center of member 1c by pivot 7f is the cam link member 11a as shown in Figures 7, 9, and 10.

The cam plate, 11, is substantially a disk securely fastened at its center to the end of shaft 9a so as to rotate therewith as shown in Figures 7, 9, and 10. Located at the edge of its periphery and extending inward radially on the face of the cam plate 11 is the cam projection 11b as shown in Figs. 9 and 10. As the cam link member 11a rides over the cam projection as shown in Figs. 9 and 10, as the cam plate, 11, turns, the cam link

member is caused thereby to shift laterally with respect to axle 4; and in doing so, through link member 1c, transmits the same motion, which is greater in magnitude at pivot 7d than at pivot 7f, to the clutch collar 7 thereby causing the clutch members 6a and 5f to disengage as shown in Fig. 7.

Shaft 9a to which cam plate 11 is secured and also to which the gear 9 is fixed coaxially is carried by the bifurcated gear bracket 10 as is shown best in Figs. 1 and 7; and the gear 9 is located between the arms of this bracket 10. Between the gears 9 and 5 and in constant mesh with the aforesaid gears and similarly disposed, between the arms of gear bracket 10, as is gear 9, and secured thereto is the gear 8, all as shown in Figs. 1 and 7.

It will be noted, as a consequence of the foregoing, that when the clutch, which is composed of members 5f, 6 and 7 is disengaged the cam plate 11 will not be moving since it receives its motion from gear 5, which is floating on shaft 4, through gears 8 and 9; and further, that the cam plate 11 cannot move until clutch members 5f and 6a become engaged since the motivating force is transmitted to 6a from axle 4 through pin 6b. With this arrangement it will also be seen that the clutch jaws 5g and 6f cannot remain engaged for more than one complete revolution of the cam plate 11 since the cam projection 11b will cause them to become disengaged through link members 11a and 1c and clutch collar 7. Pivotally connected to cam plate 11 by means of nut and bolt member 12a, as shown in Fig. 9, is the elevator link member 12. At the opposite end of shaft 9a and integrally connected therewith is a crank member 9b; pivotally connected to this crank member by means of nut and bolt member 13a, as shown in Fig. 7, is another elevator link member 13. The throw about shaft 9a for pin 12a is equal to that for pin 13a. Referring to Figs. 1 and 11 it will be seen that the upper ends of elevator link members 12 and 13 are pivotally connected with the lower ends of elevator slides 16a and 15a, respectively, and that said elevator slides ride within channels 16b and 15b respectively of elevator guides 15 and 16. Said elevator guides are upright in position and between frame members 1e and 1f, guide member 15 being secured at its lower end to frame member 1e and guide member 16 at its lower end to frame member 1f. Members 1e and 1f, it will be noted, are positioned in a spaced apart relation to each other and parallel to the longitudinal frame members 1a and 1b; and are secured at their rear ends to and upon frame cross member 19. Respectively secured to elevator slide members 15a and 16a and in conjunction with and secured to elevator topping pan 14, are the members 15c and 16c. These members 15c and 16c serve not only to hold the pan member 14 between them, but also to hold the slide members 15a and 16a within the channels of their respective guide members 15 and 16. All this is best shown in Fig. 11. Therefore, as shaft 9a rotates, slide members 15a and 16a will reciprocate within their respective channels 15b and 16b thereby through members 15c and 16c elevating and lowering elevator pan 14. Respectively secured to the upper ends of members 15 and 16 are the support members 18a and 18b as shown in Figs. 1, 5, and 11. Transversely positioned between the support members 18a and 18b in such a way that it can rotate but will have no transverse motion is the

shaft 17a, as shown in Figs. 1, 5, and 11. Coaxially secured to said shaft and centrally positioned between support members 18a and 18b is the cylindrically shaped member 17a, and secured to its periphery and radially extending away therefrom is scoop 17c as shown in Figs. 1, 5, and 11. Securely connected at its one end to shaft 17a is the arm member 17d. Pivotal connected with the other end of arm member 17d is the connecting link 16d, said link member 16d also being pivotally connected by its other end with elevator slide 16a. Hence as elevator slide reciprocates scoop member 17c is rotated about shaft 17a by arm 17d and link 16d. It will be noted here that the above mentioned parts, especially the elevator pan 14 and scoop 17c, are so coordinated that as the elevator pan 14 is raised from the position shown by solid line to that indicated by broken line in Fig. 1, the scoop member 17c is rotated clockwise from the position shown by solid line to that shown by broken line so that anything within pan 14 will be moved rearwardly with respect to the machine as a whole. Also, it will be noted that the elevator pan 14 is V shaped in its cross section and that the end of the scoop coming within the pan is correspondingly shaped as seen best in Fig. 11.

In conjunction with the elevator pan 14 is a conveyor mechanism which moves rearwardly and upwardly, and is composed principally of conveyor sprockets 23 and 24, conveyor chain 25, and conveyor guides 26 as seen in Fig. 1. The guides 26 are two in number and are positioned so as to form a V shaped trough with an opening at its apex and extending the entire length of the conveyor as best shown in Figs. 1 and 5. These guides 26 are pivotally supported at their rear and upper ends upon cross member 1g by straps 26a as shown in Fig. 1. Cross member 1g in cross section is circular and is positioned transversely within frame 1, one end being rigidly secured to member 1a and the other rigidly secured to 1b; at the lower and forward ends of conveyor guides 26 and pivotally connected thereto are the digger points 27 as shown best in Figs. 1 and 3. The digger points are also two in number, one for each guide member 26, and are so shaped that, when in position for use in the spaced apart relation shown in Fig. 3, their tips 27b are farther apart than their heels 27c, and, further, the tips 27b are slightly lower than heels 27c as seen best in Fig. 1. In Fig. 3, the digger points are shown rigidly secured to supports 28a also, said supports being integral with digger elevator 28. It will be noted that said digger member elevator is substantially an inverted U and that its sides, which are straight, ride within channel members 28b and 28c. In Figs. 1 and 3 the digger points 27 and elevator 28 are shown at their extreme lowered position, and in Fig. 1 these are shown by broken line in their extreme raised position, it being noted that when in this extreme raised position those said digger points will be above the surface of the ground.

In Fig. 3 the channel member 28b is shown as being riveted near its upper end to a short longitudinally disposed frame member 1h and this member 1h in Fig. 4 is shown rigidly secured at its end to a transverse cross member 1i and a stub 1j. The transverse cross member 1i is rigidly secured at its ends between longitudinal frame members 1a and 1b. Channel member 28c is rigidly secured, in a manner similar to the securing of channel member 28b, to a short longitudinal frame member 1k; and member 1k is

rigidly secured by its ends between transverse member 1i and stub member 1m in a manner similar to the way that member 1h is shown secured between member 1i and stub member 1j in Fig. 4. Between the underside of frame member 1b and the lower end of channel member 28b, brace member 28d is secured; and between the underside of frame member 1a and the lower end of channel member 28c, brace member 28e is secured, all as shown in Fig. 3. Between the inner ends of stub members 1j and 1m, and rigidly secured thereto by its own ends, is positioned cross member 1n, as shown in Figs. 1 and 3, to serve as additional support for elevator guides 28b and 28c and also to strengthen frame 1.

To the lower ends of the sides of elevator 28 are secured brackets 28f and 28g, and rigidly secured therein are the ends of shaft 24a, it being noted that the ends of this shaft 24a are bent so as to be approximately perpendicular to the main portion, as shown in Figs. 3 and 4. Centrally positioned on shaft 24a between the sides of elevator 28 and above the lower ends of conveyor guides 26, is conveyor sprocket 24 which is held in its central position thereon by means of cotter pins 24b and 24c. Integrally connected to the hub 24d of sprocket 24 are two sets of conveyor elements, 24e and 24f, one set near each end of the sprocket hub, as seen best in Figs. 1 and 3. It will be noted in Fig. 1 that these conveyor elements, 24e and 24f, are neither tangential with the periphery of sprocket hub 24d nor do they extend radially away therefrom, but that they are in a position in between these two. It will be noted further that since sprocket 24 turns clockwise as seen in Fig. 1, the tip of these conveyor elements 24e and 24f in turning will lead the base, or portion, where said conveyor elements are secured to the conveyor hub 24d. By being positioned in this manner, the conveyor elements will offer greater resistance to bending when engaging the beets.

As an integral part of the conveyor sprocket 24, are the sprocket teeth 24g, which engage the conveyor chain 25. This chain 25 is provided with conveyor elements 25a which also serve to link the chain together. The element 25a before becoming an integral part of conveyor chain 25, is U shaped, but after the chain links 25b are positioned upon element 25a, the ends thereof are bent into the shape shown in Figs. 1, 3, and 5, it being noted that the tip of element 25a, as the conveyor chain moves, leads the part securing links 25b together. Also it should be noted that the elements 25a do not all extend from one side of chain 25, but alternately from each side.

At the upper and rearward end of the conveyor is conveyor sprocket 23. It is centrally positioned upon shaft 23a, and is free to rotate thereon, but is secured in its central position so that it may not move transversely upon shaft 23a. Engaging its teeth 23e is the conveyor chain 25; and positioned about the periphery of the hub 23b near each end are the conveyor elements 23f and 23g. This sprocket 23 is like sprocket 24 in all respects excepting from the hub 23b is the hub extension 23c, and at the end of this extension 23c and integral therewith is a sprocket 23d which is of smaller diameter than sprocket 23 as seen best in Fig. 5. Engaging the teeth of sprocket 23d is a link chain 4g. This chain 4g is driven by a sprocket 4h which is rigidly secured to axle 4 and turns therewith as seen in Figs. 1 and 5. Hence it will be seen that as axle 4 turns, as the beet harvesting and topping machine rolls for-

- ward, the sprocket 4h will turn and drive sprocket 23d through chain 4g, and that as sprocket 23d is turned conveyor chain 25 is turned and sprocket 24 is turned. Referring to Figs. 1 and 5 it will be seen that as the machine rolls forward, and because of the arrangement of the sprockets and chains, the sprocket 23 will be turned in such a direction that conveyor chain 25 will move so that it will convey beets from the lower and forward end to the upper and rearward end of the conveyor, from which point the beets will be discharged onto the forward end of elevator pan 14, and it will be seen also that simply by changing any one or all of sprockets 23, 23d, and 4h for sprockets of different diameters that the rate at which sprocket 23 turns with respect to the rate at which rear wheels 2 and 3 turn may be altered to suit the circumstances; and that in this manner the rate at which the beets are conveyed to elevator topping pan 14 may be controlled, having due regard, however, to the distance between the beets as growing in the ground. Further, it is well to note at this point, that as the machine moves forward, the digger points 27 when in their lower position, on passing through the ground, engage the beets at their under receding sides and lift them from the ground. This is so because as the machine moves forward, or what is the same, as the beets move rearward with respect to the digger points 27, those beets coming between the said digger points 27 are elevated as they pass from the points 27b toward the heel 27c, as will be seen by Fig. 1. At about the time a beet reaches the heel 27c its top, since the beet grows in an upright position, is engaged by the conveyor elements 24e, 24f, and 25a, and because of the direction of travel of elements 24e, 24f, and 25a at this point, which is toward the rear of the machine, the beet is pulled out of the ground and over onto the conveyor guides 26, top first; and it is in this position that the beet is dragged up the conveyor, between guides 26 by its engagement with conveyor chain elements 25a, and delivered onto elevator topping pan 14, it being noted that the opening along the bottom side and between conveyor guides 26 as herein before described is not great enough to allow any of the beets to fall to the earth but that it is sufficiently large to allow any soil to fall through onto the ground.
- 50 The beets, as they are delivered onto the topping pan 14, are pushed, tops first, against stop member 19a which is an integral part of clutch link member 19, as seen in Figs. 1 and 11. Member 19 is pivotally mounted between the arms of gear bracket 10 as shown in Figs. 1 and 7. In Figs. 1 and 7 it will be seen that the lower end of link member 19 engages one end of link member 11c, that said link 11c is pivotally secured to transverse frame member 1c at its under side by pivot 11d, that to the other end of link 11c is pivotally secured link 11e by one end and that the other end of link 11e is pivotally secured to link 11a. Hence it will be seen that as stop member 19a is pushed backwardly by beets coming onto topping elevator pan 14, through the hereinbefore described linkage composed of members 11c, 11e, 11a, 7c, and clutch collar 7, the clutch jaws 5g and 6a will become engaged thereby causing elevator pan 14 to raise as hereinbefore described.
- 70 As a means to sever the beet tops from the beets as the topping pan 14 is elevated there is provided a sharp edged blade 15d which is rigidly secured in a transverse position between elevator guides 14 and 15 with the sharp edge down, all as best shown in Figs. 1 and 11. The

blade 15d is so positioned that as the rearward end of elevator pan 14 passes by there will be a shearing action provided for, the beet tops protruding beyond the end of said elevator pan. When the pan 14 reaches the top of its stroke the beet thusly topped is discharged from the pan by scoop member 11c which is coordinated with elevator pan 14, all as hereinbefore described. The beet on being discharged from elevator pan 14 will fall into a hamper, not shown, positioned at the rear of the beet topping and harvesting machine. The beet tops will fall to the ground as they are cut from the beets.

In Figs. 1 and 5 it will be seen that sprocket 23 is rotatably mounted upon shaft 23a, that to the ends of shaft 23a are rigidly secured slide blocks 20a and 21a, and that said blocks are positioned within the channelled portions of conveyor sprocket supports 20 and 21, said supports 20 and 21 being upright in position and rigidly secured at their lower ends respectively to longitudinal frame members 1a and 1b. To block 20a is rigidly secured by one end shaft 20b, the shaft being positioned vertically within the channelled portion of member 20 and extending upwardly from the block 20a; shaft 21b is rigidly secured by one end to block 21a, is vertically positioned within channelled portion of member 21 and extends upwardly from block 21a, all as seen in Figs. 1 and 5. To the tops of conveyor sprocket support members 20 and 21 is rigidly secured transverse member 22 which serves to hold members 20 and 21 in spaced apart relation. It will be noted that the ends of shafts 20b and 21b extend through and above member 22 as seen best in Figs. 1, 5, and 6. Shaft 21 is provided with a pin 21c upon which is positioned collar 21d; between collar 21d and member 22 is positioned helical spring 21e. On the upper end of shaft 21 is threaded nut 21h; immediately below this nut 21h is collar 21g; and between this collar 21g and member 22 is positioned helical spring 21f. Shaft 20 is similarly provided with pin and collar (not shown), spring 20e, spring 20f, collar 20g and nut 20h. Because of this arrangement of the above described parts, shaft 23a can move vertically up or down carrying sprocket 23 with it; but its motion is within the limits of compression of the springs 20e and 21e or 20f and 21f. Blocks 20a and 21a serve to guide the movement within the channels of members 20 and 21. This arrangement is provided so that the sprocket 23 and the conveyor elements 23f and 25a will adjust themselves within conveyor guides 26 to the size of the beets.

The digger points, as hereinbefore described, are secured to elevator 28. Also secured to this elevator, 28, by means of brackets 28f and 28g is the shaft 24a upon which is positioned the sprocket 24 as has been described. Because of this relation of sprocket 24 to elevator 28 and digger points 27 to elevator 28, it will be seen that as one is elevated or lowered so is the other. As the digger points are shifted up or down, and because they are rigidly secured to conveyor guides 26, said guides will also be shifted at their front and lower ends in a like manner, the rear and upper ends of conveyor guides pivoting about cross member 1g. To accomplish all this the elevator 28 is provided at its upper end with brackets 28h and 28i, said brackets being rigidly secured to elevator 28. Secured by one end in a position between said brackets 28h and 28i by means of a pin is the link member 28j. This link member 28j is bifurcated at its other end, and

5 pinned thereto between the bifurcated portions by one end is another link member 28k. By its other end link 28k is rigidly secured to the end of shaft 1p, all as seen in Figs. 1 and 3. Referring to Figs. 1 and 3 it will be seen that shaft 1p is positioned directly above frame cross member 1i and is secured thereto by one end by journal brackets 1q and 1r, shown in Fig. 3, and that link member 28k is positioned between these journal brackets. At its other end shaft 1p is journaled 10 within journal 1s, said journal being rigidly secured upon longitudinal frame member 1a. Secured on this shaft 1p is a gear 28m which meshes with another gear 28o which is secured on a shaft 15 28n, which shaft 28n is also journaled in the journal 1s, and on the extended end of the shaft 28n is a hand wheel 28p, thus providing means for operating the digger elevator 28. By turning the hand wheel 28p the shaft 28n is turned 20 which turns the gear 28o which in turn revolves the gear 28m and therewith the shaft 1p which operates the link members 28j and 28k thus raising or lowering the elevator 28. The front wheels 29 are connected with the front portion 25 of the frame 1 by a substantially conventional 5th wheel arrangement consisting of supports 29a which extend downwardly from the frame 1 and to which is secured a wheel member 29b which rides upon another wheel member 29c, 30 which wheel 29c, is supported on a member 29d which is provided with an upwardly extending portion forming a king pin for the 5th wheel arrangement, all of which is shown best in Figs. 1 and 2 of the drawings.

35 In Figs. 12 and 13 is shown the connection of the rear or traction wheels 2 and 3 with the axle 4 which provides operation of the axle with the forward movement of the traction wheels 2 and 3 but releases from the shaft 4 with any backward movement and consists of cam portions 2a positioned in the hub 2b of the wheel 2 and interposed between these cam portions 2a and the axle 4 are rollers 2c. Thus when the hub moves in one direction relative to the axle 4 these bearings bind upon the axle, while when moved in the opposite direction they are released from the axle and permit the free movement of the axle relative to the hub.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

60 1. In a beet harvesting and topping machine, a frame member, traction wheels for supporting one end of said frame member, an axle in connection with said traction wheels, beet digger and puller members pivotally supported on said frame in elevating position, and means mounted on the front portion of said frame in connection with said digger members including link, gear, and hand wheel means for raising and lowering the same at their front ends.

70 2. In a beet harvesting and topping machine, a frame member, traction wheels for supporting one end of said frame member, an axle in connection with said traction wheels, beet digger and puller members pivotally supported on said frame 75 in elevating position, means mounted on the

front portion of said frame in connection with said digger members including link, gear, and hand wheel means for raising and lowering the same at their front ends, and a movable conveyor positioned contiguous to said digger members provided with extended engaging portions adapted to move between said digger members for elevating beets with their tops rearwardly. 5

3. In a beet harvesting and topping machine, a frame member, traction wheels for supporting one end of said frame member, an axle in connection with said traction wheels, beet digger and puller members pivotally supported on said frame in elevating position, means mounted on the front portion of said frame in connection 10 with said digger members including link, gear, and hand wheel means for raising and lowering the same at their front ends, a moveable conveyor positioned contiguous to said digger members provided with extended engaging portions 15 adapted to move between said digger members for elevating beets with their tops rearwardly, and a reciprocable topper member operable by the shaft connected with the traction wheels in the rear portion of said conveyor adapted to engage 20 and cut the tops from the beets. 25

4. In a beet harvesting and topping machine, a frame member, traction wheels for supporting one end of said frame member, an axle in connection with said traction wheels, beet digger 30 and puller members pivotally supported on said frame in elevating position, means mounted on the front portion of said frame in connection with said digger members including link, gear, and hand wheel means for raising and lowering 35 the same at their front ends, a moveable conveyor positioned contiguous to said digger members provided with extended engaging portions adapted to move between said digger members for elevating beets with their tops rearwardly, 40 a reciprocable topper member operable by the shaft connected with the traction wheels in the rear portion of said conveyor adapted to engage and cut the tops from the beets, and means for automatically stopping and starting said topper 45 operated by the movement of the beets on the conveyor.

5. In a beet harvesting and topping machine, a frame member supported at its rear end on traction wheels and supported at its front end 50 on fifth wheel connecting means wheels, an axle in connection with said rear traction wheels provided with means for releasing the axle from said wheels when said frame is moved backwardly but engaging said wheels when said frame is moved forwardly, a beet topper operatively connected with said rear axle positioned on said frame, cam and clutch means in connection with said rear axle and said beet topper for releasing said top- 55 per from said rear axle with each revolution of said shaft, and trigger means for reengaging said topper with said shaft operable by the movement of said beets, and a conveyor pivotally mounted on said frame with its rear end in close proximity to said topper and its front end inclined forwardly and downwardly. 60

6. In a beet harvesting and topping machine, a frame member supported at its rear end on traction wheels and supported at its front end on fifth wheel connecting means wheels, an axle 70 in connection with said rear traction wheels provided with means for releasing the axle from said wheels when said frame is moved backwardly but engaging said wheels when said frame is moved forwardly, a beet topper operatively con- 75

nceted with said rear axle positioned on said frame, cam and clutch means in connection with said rear axle and said beet topper for releasing said topper from said rear axle with each revolution of said shaft, and trigger means for re-engaging said topper with said shaft operable by the movement of said beets, a conveyor pivotally mounted on said frame with its rear end in close proximity to said topper and its front end inclined forwardly and downwardly, and digger and puller members secured on the front end of said conveyor.

7. In a beet harvesting and topping machine, a frame member supported at its rear end on traction wheels and supported at its front end on fifth wheel connecting means wheels, an axle in connection with said rear traction wheels provided with means for releasing the axle from said wheels when said frame is moved backwardly but engaging said wheels when said frame is moved forwardly, a beet topper operatively connected with said rear axle positioned on said frame, cam and clutch means in connection with said rear axle and said beet topper for releasing said topper from said rear axle with each revolution of said shaft, and trigger means for re-engaging said topper with said shaft operable by the movement of said beets, a conveyor pivotally mounted on said frame with its rear end in close proximity to said topper and its front end inclined forwardly and downwardly, digger and puller members secured on the front end of said conveyor, and elevator means on the front portion of said frame engagement with said digger and puller members for raising and lowering said digger members together with the front portion of said conveyor.

8. In a beet harvesting and topping machine, a frame member supported at its rear end on traction wheels and supported at its front end on fifth wheel connecting means wheels, an axle in connection with said rear traction wheels provided with means for releasing the axle from said wheels when said frame is moved backwardly but engaging said wheels when said frame is moved forwardly, a beet topper operatively connected with said rear axle positioned on said frame, cam and clutch means in connection with said rear axle and said beet topper for releasing said topper from said rear axle with each revolution of said shaft, and trigger means for re-engaging said topper with said shaft operable by the movement of said beets, a conveyor pivotally mounted on said frame with its rear end in close proximity to said topper and its front end inclined forwardly and downwardly, digger and puller members secured on the front end of said conveyor, elevator means on the front portion of said frame engaged with said digger and puller members for raising and lowering said digger members together with the front portion of said conveyor, and another conveyor member moveable relatively to said first mentioned conveyor with extending portions interposed between the members of said first mentioned conveyor member for conveying beets upwardly and backwardly on said conveyor member.

9. In a beet harvesting and topping machine, a frame member supported at its rear end on traction wheels and supported at its front end on fifth wheel connecting means wheels, an axle in connection with said rear traction wheels provided with means for releasing the axle from said wheels when said frame is moved backwardly but engaging said wheels when said frame

is moved forwardly, a beet topper operatively connected with said rear axle positioned on said frame, cam and clutch means in connection with said rear axle and said beet topper for releasing said topper from said rear axle with each revolution of said shaft, and trigger means for re-engaging said topper with said shaft operable by the movement of said beets, a conveyor pivotally mounted on said frame with its rear end in close proximity to said topper and its front end inclined forwardly and downwardly, digger and puller members secured on the front end of said conveyor, elevator means on the front portion of said frame engagement with said digger and puller members for raising and lowering said digger members together with the front portion of said conveyor, another conveyor member moveable relatively to said first mentioned conveyor with extending portions interposed between the members of said first mentioned conveyor member for conveying beets upwardly and backwardly on said conveyor member, and said moveable conveyor consisting of chain and sprockets and said chain provided with extending beet engaging portions.

10. In a beet harvesting and topping machine, a frame member, traction and caster wheels supporting said frame member, an axle in connection with said traction wheels engageable therewith when said frame moves forwardly only, a moveable chain conveyor operatively connected with said axle, a beet topper operatively connected with said axle, cam and clutch means in connection with said axle and said topper adapted to be shifted with the movement of beets so that said topper automatically stops and operates dependent upon the movement of the beets.

11. In a beet harvesting and topping machine, a frame member, traction and caster wheels supporting said frame member, an axle in connection with said traction wheels engageable therewith when said frame moves forwardly only, a moveable chain conveyor operatively connected with said axle, a beet topper operatively connected with said axle, cam and clutch means in connection with said axle and said topper adapted to be shifted with the movement of beets so that said topper automatically stops and operates dependent upon the movement of the beets, and a combined digger member and conveyor members with their rear portions pivotally mounted on said frame and means for raising and lowering said digger members and the front portions of said conveyor members.

12. In a beet harvesting and topping machine, a frame member, traction and caster wheels supporting said frame member, an axle in connection with said traction wheels engageable therewith when said frame moves forwardly only, a moveable chain conveyor operatively connected with said axle, a beet topper operatively connected with said axle, clutch means in connection with said axle, said topper adapted to be shifted with the movement of beets so that said topper automatically stops and operates dependent upon the movement of the beets, and a combined digger member and conveyor member with their rear portions pivotally mounted on said frame, means for raising and lowering said digger members and the front portions of said conveyor members, and consisting of link, gear and hand wheel means.

13. In a beet harvesting and topping machine, a frame, wheels for supporting said frame, digger and puller members supported on said frame in-

- termidate its sides consisting of forwardly diverging digger members with their front ends inclined downwardly adapted to engage the beets in their lower receding portions and raise the
- 5 same with the forward movement of said digger members, and a conveyor in connection with said digger members including spaced stationary members providing dirt releasing space, chain and sprocket means movable relatively thereto,
- 10 both chain and sprockets provided with extending beet top engaging portions interposed between said stationary conveyor members.
14. In a beet harvesting and topping machine, a frame, wheels for supporting said frame, digger and puller members supported on said frame intermediate its sides consisting of forwardly diverging digger members with their front ends inclined downwardly adapted to engage the beets in their lower receding portions and raise the
- 15 same with the forward movement of said digger members, a conveyor in connection with said digger members including spaced stationary members providing dirt releasing space, chain and sprocket means movable relatively thereto,
- 20 both chain and sprockets provided with extending beet top engaging portions interposed between said stationary conveyor members, and a topper member on the rear portion of said frame elevated from said digger members adapted to engage and top the beets motivated by said conveyor.
16. In a beet harvesting and topping machine, a frame, wheels for supporting said frame, digger and puller members supported on said frame intermediate its sides consisting of forwardly diverging digger members with their front ends inclined downwardly adapted to engage the beets in their lower receding portions and raise the
- 25 same with the forward movement of said digger members, a conveyor in connection with said digger members including spaced stationary members providing dirt releasing space, chain and sprocket means movable relatively thereto,
- 30 both chain and sprockets provided with extending beet top engaging portions interposed between said stationary conveyor members, and a topper member on the rear portion of said frame elevated from said digger members adapted to engage and top the beets motivated by said conveyor, means for receiving said beets and means for removing the tops.
- 15 same with the forward movement of said digger members, a conveyor in connection with said digger members including spaced stationary members providing dirt releasing space, chain and sprocket means movable relatively thereto,
- 20 both chain and sprockets provided with extending beet top engaging portions interposed between said stationary conveyor members, and a topper member on the rear portion of said frame elevated from said digger members adapted to engage and top the beets motivated by said conveyor, and means for receiving said beets and means for removing the tops.
- 25 same with the forward movement of said digger members, a conveyor in connection with said digger members including spaced stationary members providing dirt releasing space, chain and sprocket means movable relatively thereto,
- 30 both chain and sprockets provided with extending beet top engaging portions interposed between said stationary conveyor members, and a topper member on the rear portion of said frame elevated from said digger members adapted to engage and top the beets motivated by said conveyor, means for receiving said beets and means for removing the tops, and said topping means, said top removing means, and said conveyor and all operating parts operated from the traction 35 wheel axle.

LOUIS A. GEIBIG.
